TOILET FLUSH VALVE

Lloyd Allen, Jr., San Bernardino, Calif.

Application May 16, 1952, Serial No. 288,266

2 Claims. (Cl. 4—57)

1

This invention relates to toilet flush valves. More particularly, the invention is an improved valve assembly capable of substitution for the conventional valve assembly now in use.

Flush tank valves of the type having a stem secured to a ball and working through a guide means on the overflow pipe tend, in time, toward improper seating of the ball. This is due to the fact that the stem and guides wear, causing lateral deviation of the ball in its movement toward the valve seat.

Important objects of the invention are, therefore, to provide a valve assembly that will result in proper seating of the ball in every instance; will be capable of substitution for assemblies already in use, without modification or re-designing of existing tank fixtures; will operate in a manner to facilitate disengagement of the ball from its seat; will be inexpensive and durable; and will be capable of installation in minimum time and with maximum ease.

Other objects will appear from the following description, the claims appended thereto, and from the annexed drawing, in which like reference characters designate like parts throughout the several views, and wherein:

Figure 1 is a top plan view, in which the tank is illustrated fragmentarily and in section;

Figure 2 is a sectional view on line 2—2 of Figure 1;

Figure 3 is a sectional view on line 3—3 of Figure 2; and

Figure 4 is a sectional view on line 4—4 of Figure 2.

A conventional flush tank has been shown, having a vertical front wall 10, and a bottom wall 12 provided with a dependently flanged opening 14. Sealing rings 16 are engaged against the flange of opening 14 by a nut 18 threaded on the flush pipe 20, said pipe being integral at its upper end with an overflow pipe support 22, engaging the lower end of the vertically positioned overflow pipe 24. A sealing washer 26 is engaged between the pipe 20 and the edge of the opening 14 to prevent leakage.

Mounted upon the overflow pipe is a stem guide having a ring 28 at one end circumposed about the overflow pipe and secured thereto in selected positions of vertical adjustment by a set screw 29. A lateral arm is integral with the ring 28 and is bifurcated at its outer end, the fork arms 32 thereof having stem guide openings 34.

All this is conventional and does not per se form part of the invention. Usually, a stem, not

shown, is vertically reciprocable in openings 34. However, the invention permits removal of said stem, and installation of the improved valve assembly, with the conventional stem guide becoming a mounting bracket.

The improved assembly 36 includes a cage formed with a circumferential series of vertical rods 38, a plurality of vertically aligned, arcuate bands 40 being fixedly connected to the rods at locations spaced longitudinally of the rods.

Some of the rods have inclined extensions 42 at their upper ends, the several extensions converging upwardly and being made rigid, at their convergent ends, with an annular abutment 44 concentric with the bands 40.

Extended through the abutment is a bolt 46, the head of which is engaged against the lowermost fork arm 32. A wing nut 48 is then threaded on the bolt and engages against the abutment 44. In this way, the cage is forced against the bottom wall 12 and is fixedly positioned in concentric relation to a valve seat 49 formed upon the flush pipe.

A ball 50 is of generally conventional shape, but has a flat bottom wall 52 formed with a large opening in which is engaged a weight 54, said weight having a circumferential groove 56 receiving the edge of the opening. An eye 58 is secured to the upper end of the ball and a chain 60 or similar flexible element is attached to the eye. The chain 60, at its upper end, is connected to the outer end of an angular extension 62 of an operating arm 64 swingable in a vertical plane by operation of a handle 66 mounted on the wall 10. Arm 64 and its associated extension 62, and handle 66, are conventional parts of the tank assembly.

Figures 1 and 2 show that the outer end of the extension 62, and the eye 58, are out of vertical alignment. Therefore upward pull on the ball 50 is exerted through an inclined path, so as to facilitate movement of the ball 50 off its seat. Only slight pressure on the handle 66 need, therefore, be exerted, as distinguished from conventional arrangements, wherein the ball moves off its seat vertically with said vertical movement being resisted by a suction set up at the valve seat.

It is to be noted that when the ball is lifted off its seat, it is free-floating within the cage, and will be effectively stabilized while off the seat by the weight 54. As a result, when the ball is to return to its seat, it will be guided thereto by the natural flow of water through the flush pipe, the weight being of prime importance in this

respect, since it retains the ball in a stabilized condition during the return or downward movement of the ball.

It is also an important characteristic of my construction that the entire assembly is specifically designed as one that can be substituted for the conventional type having a vertically reciprocable stem. One need only remove the old ball and stem; mount the cage with ball 50 inside it, between the guide and bottom wall as discussed above; and attach the chain to the extension 62.

In this regard, the device is adapted to be mounted in any of various makes of tank assemblies. Some of these have guides higher, or lower, than others. This is immaterial, however, because the distance between the abutment 44 and the bottom wall 12 need not be pre-set, as long as the bolt 46 is sufficiently long to extend through both the guide and the abutment.

It is believed apparent that the invention is not necessarily confined to the specific use or uses thereof described above, since it may be utilized for any purpose to which it may be suited. Nor is the invention to be necessarily limited to the specific construction illustrated and described, since such construction is only intended to be illustrative of the principles of operation and the means presently devised to carry out said principles, it being considered that the invention comprehends any minor changes in construction that may be permitted within the scope of the appended claims.

What is claimed is:

1. In a flush tank valve assembly, the combination, with a laterally projected cage support member of a flush tank, said member having an opening, of a cage generally circular in cross-section and adapted to be circumscribed about and extend upwardly from a valve seat provided in the bottom wall of the tank, said cage being formed open at its lower end for positioning of the cage over the valve seat, and having a small annular abutment at its upper end aligned vertically with and spaced from said opening; a bolt extending through the opening and abutment and having its head engaged against said support member; a nut threaded on the bolt and engaging the abutment to force the lower end of the cage against the bottom wall of the tank; a ball valve positioned within the cage and

adapted to float upwardly and downwardly therein away from and onto said seat; a central weight at the lower end of the ball valve providing means for stabilizing the ball valve when said valve is off its seat; and means connecting the valve to a valve lift arm of the tank and arranged to exert upward and lateral pull on the ball when the ball is to be lifted off its seat.

2. In a flush tank valve assembly, the combination, with a laterally projected cage support member of a flush tank, said member having an opening, of a cage generally circular in cross-section and adapted to be circumscribed about and extend upwardly from a valve seat provided in the bottom wall of the tank, said cage being formed open at its lower end for positioning of the cage over the valve seat, and having a small center opening at its upper end aligned vertically with and spaced from said support member opening; a bolt extending through the support member and cage openings and having its head engaged against said support member; a nut threaded on the bolt and engaging the upper end of the cage to force the lower end of the cage against the bottom wall of the tank; a ball valve positioned within the cage and adapted to float upwardly and downwardly therein away from and onto said seat; a central weight at the lower end of the ball valve providing means for stabilizing the ball valve when said valve is off its seat; and means connecting the valve to a valve lift arm of the tank, said last-named means including a flexible element attached at one end to the valve, and attached at its other end to the valve lift arm at a location out of vertical alignment with said one end, for exerting an upward pull upon the valve through an inclined path, thus to cause the initial upward movement of the valve off its seat to be directed laterally of the seat.
